UNITED STATES PATENT OFFICE.

BENJAMIN WOLHAUPTER, OF NEW YORK, N. Y., ASSIGNOR TO THE RAIL JOINT COMPANY, OF NEW YORK, N. Y., A CORPORATION OF NEW YORK.

REINFORCED ANGLE-BAR FOR RAIL-JOINTS.

No. 858,774.

Specification of Letters Patent.

Patented July 2, 1907.

Application filed October 6, 1906. Serial No. 337,745.

To all whom it may concern:

Be it known that I, BENJAMIN WOLHAUPTER, a citizen of the United States, residing at New York city, in the county of New York and State of New York, have 5 invented certain new and useful Improvements in Reinforced Angle-Bars for Rail-Joints, of which the following is a specification.

This invention relates to the art of rail joints, and has special reference to an improved construction of angle 10 bar of the type commonly termed splice bars.

To this end the invention has for its main and primary object a simple, practical, and thoroughly efficient angle bar of reinforced construction, and co-operating with the rail ends in such a manner as to provide 15 a rail joint of maximum strength and efficiency. At the same time, the improved angle bars may be applied with all the facility and readiness of the conventional forms of splice bars or fish plates, and not interfere in the least with the tamping of the road bed.

20 A special object of the invention is to construct the reinforced angle bar along practical engineering lines that will secure, in the most effective manner, the functions of supporting and trussing the rail ends at the most effective points, while at the same time preserving 25 in the formation of the bar, the maximum strength with a minimum amount of material. Also, in this connection, an important feature of the invention resides in providing a reinforced angle bar possessing exceptional strength and a powerful trussing action without sacrificing any of the necessary qualities of proper weight 30 and rigidity, and sufficient resiliency.

With these and other objects in view, which will readily appear to those familiar with the art, as the nature of the invention is better understood, the same 35 consists in the novel construction, combination and arrangement of parts hereinafter more fully described, illustrated and claimed.

The essential feature of the invention involved in the practical and effective combination of several mechanical details of construction, is susceptible to modification 40 without departing from the scope of the invention, but certain preferred embodiments of the latter are shown in the accompanying drawings, in which—

Figure 1 is a sectional perspective view embodying 45 in its construction the improved reinforced angle bars claimed herein. Fig. 2 is a side elevation of the joint equipped with the improved angle bars. Fig. 3 is a cross sectional view on the line 3—3 of Fig. 2. Fig. 4 is a similar view showing a modification in the disposition 50 of the stiffening girder with reference to the base supporting shoulder at the top thereof. Fig. 5 is a similar view of another modification illustrative of another form in which the angle bar may be rolled to provide

the pendent stiffening girder and base supporting shoulder for the rail base. 55

Like references designate corresponding parts in the several figures of the drawings.

The improvements contemplated by the present invention are intended to provide a design of angle bar or splice bar which not only provides the bar with the necessary strength, weight, and resiliency, but also secures one of the practical and important features of that type of rail joints known to railroad engineers as the continuous, Weber, and Wolhaupter rail joints, namely, that of providing a base support or trussing 60 bridge for the rail ends beneath the base of the rail, thereby correcting the tendency of the metal of the angle bars to flow away from beneath the head of the rail at its ends on account of the excessive loads per unit of area. Such flowing leaves a space between the 65 rail head and angle bar allowing the rail to pound the angle bar, thereby causing the same to rupture or buckle under the deflecting pressure of the load. 70

In carrying out the invention no change is required 75 in the general features of the rail joint, so a rail joint embodying the present invention may simply comprise the adjoining rail ends A—A, the opposite side angle bars 1—1, and the joint bolts b passing through the aligned bolt holes in the angle bars and the rails, said angle bars also having suitably arranged spike-notches S. 80

In the form of rail joint illustrated in the drawings, the opposite side angle bars 1 are of duplicate design, and both embody the mechanical improvements forming the subject-matter of the present invention. Each 85 of said bars 1 is formed by the usual rolling, shearing and setting up processes usually employed in the manufacture of rail joint angle bars, though the peculiar design of the improved reinforced angle bar necessarily requires certain modifications of these processes, which, however, form no part of the present invention 90 and are not claimed herein.

Referring in detail to the design of each angle bar 1, it will be observed that the same essentially consists of a main straight splice-bar portion 2, fitting in the angle or channel of the rail ends, extending across the 95 joint, and overlying the rail ties T supporting the rails. The main splice bar portion 2 of each angle bar is formed at its top edge with a thickened or flanged bearing head 3 whose inclined face abuts against the under inclined face of the rail head. At its lower edge, the 100 main bar portion of the angle bar is formed with a foot flange 4 fitting snug against the upper inclined bearing face 5 of the rail base 6, and a distinctive feature of the present invention resides in forming the foot flange 4 with a horizontally offset resilient folded rail clasp 7. 105 This rail clasp is an integral part of the angle bar, and

projects a distance beyond the adjacent edge of the rail flange so as to leave between such edge and the bight of the clasp an open bight space 8 which contributes materially to the resiliency of the clasp, and 5 to the clasping action when the load is imposed on the rail joint. This function of the clasp is also aided by forming the same at the under side of its upper leg with a clearance flat 9 disposed at an obtuse angle to the inclined bearing face of the foot flange 4, and 10 lying clear from and above the outer portion of the upper bearing face 5 of the rail flange. It will be observed that the resilient clasp 7 projects from the central part of the bar in the vertical plane of the joint between the rail ends. This is provided for by 15 shearing off the lower edge portions of the bar, inward from the ends thereof along the shearing lines 10 to the point where an intermediate flange is left to form the clasp 7 and the integral elements directly associated therewith; said flange and its related elements 20 being designed to lie in the space between the rail ties T.

By reason of the horizontally offset disposition of the clasp 7, the lower leg thereof (designated by the number 11) is designed to extend beneath the rail base, and is 25 formed on its upper side with a base supporting shoulder 12 adapted to be held in firm trussing contact with the rail base, and to bridge the joint of the rails. An important feature of this connection is to make the base supporting shoulder 12 of greater width than the upper 30 clearing flat 9 so that the inner edge of said shoulder 12 is disposed well toward the center line of the rails, and inside of the vertical plane of the point where the flat 9 leaves the rail flange. Another important feature of the invention resides in the detail of so rolling or forming 35 the lower leg 11 of the clasp 7 that normally (before the angle bar is applied) the top surface of the supporting shoulder 12 inclines slightly upward as indicated by the dotted lines in the sectional views of the drawings. By reason of giving this normal upward inclination 40 to the supporting shoulder 12, it will be obvious that as the rail flange enters the space within the clasp, the leg 11, having the shoulder 12, will open out and give the rail flange a bearing. This action is permitted by reason of the flexibility of the angle bar at 7, and 45 the construction referred to allows for different thicknesses of rail flanges and gives them all a support on the shoulder 12.

Another important detail is the formation of the angle bar with a pendent stiffening girder or flange 13 formed 50 integrally with the lower edge 11 of the clasp 7, and substantially coextensive with such clasp. This stiffening girder reinforces and stiffens the base support 11-12 for the rail and assists in holding the shoulder 12 firmly trussed-up against the rail base. At the 55 same time, this trussing action is further aided through the action of the resilient rail clasp 7 which necessarily has somewhat of a wedging action when drawn over the rail flange by the tightening of the bolts. Also, the resiliency of the clasp 7 adapts the same to any 60 variations in the thickness of rail flanges.

In a preferred form of construction shown in Fig. 3 the stiffening girder 13 is disposed in a vertical plane, and is preferably strengthened vertically and laterally by forming the same at the inner side of its lower edge 65 with a continuous reinforce-rib 14. The important

functions described are not only preserved in connection with the construction shown in Fig. 3, but also in connection with any practical modification which retains the feature of the additional bearing support for the rail base on top of a stiffening girder which lies 70 between the ties. For instance, as shown in Fig. 4, the stiffening girder designated by the number 15, is disposed inwardly at an oblique angle; while, as shown in Fig. 5, the girder designated by the number 16 may be disposed perpendicularly in the vertical plane of the 75 bight of the clasp 7, and the lower leg of such clasp offset inwardly from the girder to provide the extended base supporting shoulder 12 referred to.

I claim:—

1. An angle bar for rail joints provided intermediate its ends with an offset resilient rail clasp, a pendent stiffening girder, and an extended base-supporting shoulder located at the top of the girder. 80
2. An angle bar for rail joints provided with an intermediate bottom extension comprising a resilient folded rail clasp offset from the foot flange of the bar and provided at the upper side of its lower leg with an extended base supporting shoulder, the said lower leg of the clasp being further provided with a pendent stiffening girder. 85
3. An angle bar for rail joints provided with an intermediate bottom extension comprising a resilient folded rail clasp offset from the foot flange of the bar and provided at the under side of its upper leg with a clearance flat and at the upper side of its lower leg with an extended base supporting shoulder, the said lower leg of the clasp being further provided with a pendent stiffening girder. 90
4. An angle bar for rail joints provided with an intermediate bottom extension comprising a resilient folded rail clasp offset from the foot flange of the bar and provided at the under side of its upper leg with a clearance flat and at the upper side of its lower leg with an extended base supporting shoulder of greater width than said flat, the said lower leg of the clasp being further provided with a pendent stiffening girder. 100
5. In a rail joint, the rail ends, and the side angle bars provided centrally between their ends with a bottom extension lying between the ties and having a resilient rail clasp embracing the rail flange, a pendent stiffening girder, and an extended base-supporting shoulder located 105 at the top of the girder and held against the rail base.
6. In a rail joint, the rail ends, and the side angle bars each provided centrally between their ends with a resilient rail clasp embracing the rail flange and having an upper clearance flat overlying the outer portion of the upper bearing face of the rail flange, said clasp being further provided on its lower leg with an extended base supporting shoulder and a stiffening girder pendent from said shoulder portion, the said base supporting shoulder snugly fitting against the rail base from the edge of its 115 flange to a point inside of the vertical plane of the point where the clearance flat leaves the bearing face of the rail flange. 120
7. In a rail joint, the rail ends, and the side angle bars each provided centrally between their ends with a horizontally offset, resilient folded rail clasp embracing the rail flange and having an open bight space beyond the edge of the rail flange, an upper clearance flat overlying the outer portion of the upper bearing face of the rail flange, said clasp, being further provided on its lower 130 leg with an extended base supporting shoulder and a stiffening girder pendent from said shoulder portion, the said base supporting shoulder snugly fitting against the rail base from the edge of its flange to a point inside of the vertical plane of the point where the clearance flat 135 leaves the bearing face of the rail flange.

In testimony whereof I hereunto affix my signature in the presence of two witnesses.

BENJAMIN WOLHAUPTER.
